UNITED STATES PATENT OFFICE.

ARTHUR B. DAVIS AND ANCEL B. LEFFEL, OF SPRINGFIELD, OHIO.

INKING DEVICE FOR PRINTING-PRESSES.

1,072,095.

Specification of Letters Patent.

Patented Sept. 2, 1913.

Application filed December 19, 1911. Serial No. 666,657.

To all whom it may concern:

Be it known that we, ARTHUR B. DAVIS and ANCEL B. LEFFEL, citizens of the United States, residing at Springfield, in the county 5 of Clark and State of Ohio, have invented new and useful Improvements in Inking Devices for Printing-Presses, of which the following is a specification.

The general object of the invention is to 10 increase the efficiency of the inking devices of printing presses by so constructing these devices as to render them less susceptible to the heat, caused by frictional contact with the printing apparatus *per se*, and consequent wearing out after a relatively short 15 period of use.

Other objects will appear and be better understood from the following description taken in connection with the accompanying 20 drawings, in which—

Figure 1 is a perspective of one embodiment of the invention also showing a sufficient portion of a printing press to illustrate one application of our device. Fig. 2 25 is a detail partly in section of one of the supports for the distributing apparatus. Fig. 3 is a sectional detail of the belt.

In carrying out our invention we arrange 30 the inking apparatus in such relation to the printing apparatus or element, as to effect frictional contact between the parts so that movement will be imparted to the inking device by the movement of the printing apparatus.

35 When arranging the device for use with a reciprocating printing apparatus we generally, but, of course, not necessarily, provide a multiple series of rolls and also prefer, although, of course, it is by no means necessary, to arrange the rolls 9—9 of each 40 series in vertical alinement and to further arrange each series spaced from the adjacent series. We also form circular enlargements 10 on the lower rolls of each series to travel 45 on the bearers 11 which are arranged on the bed and extend type-high or substantially so. The rolls 9—9 of each series are then connected by an endless belt or apron 12, the lowest portion of whose surface contacts 50 with the printing surface afforded by the material 6 in the bed 5. In this connection it may be stated that preference is given to a structure wherein the surface area of each belt corresponds approximately to that of 55 the printing surface whether such printing

surface be plane or circular as shown in Figs. 1 and 3 respectively. This construction, namely the relative areas of the inking and printing surfaces, is important since it obviates, to an appreciable extent, the loss 60 heretofore incurred in maintaining inking devices made up of a plurality of small rolls arranged to contact directly with the printing surface. To further amplify the statement of advantage of my device, over an inking surface made up of a plurality of small rolls, let the number of revolutions made by each small roll during one reciprocation or rotation of the aforesaid printing surface be considered. Thus it is seen that 70 the amount of wear on each roll is due to each point on the surface thereof contacting, for a relatively great number of times with the printing surface during one reciprocation or rotation thereof. Moreover, and 75 owing to the friction this frequent contact soon raises the temperatures of the inking rolls to an appreciable extent, in fact to such an extent that it is invariably necessary to stop the press at relatively short 80 intervals during what is known as a long run. Consequently, since the very construction of the inking rolls prohibits their losing any appreciable amount of heat through radiation while in use, the result is that the 85 composition which forms the body of these rolls is soon consumed or pitted by heat, thus rendering the rolls unfit for applying ink to the printing surface. With our construction, however, these defects are, as before stated, practically eliminated since the area of the inking surface insures that only one point thereof will contact with the printing surface during one revolution or reciprocation thereof, and moreover, the inking 90 surface (considering the belt as a whole) is especially adapted for losing heat by radiation.

The rolls of each series are preferably supported by a pair of standards secured to any convenient portion of the frame 13 and one of which is shown in Fig. 1 and designated by 14. The trunnions 15 of the upper and lower rolls turn in boxes 16—16 which are adapted to connect to the standards and 100 may be adjusted with respect to each other by the nuts 17—17 on the screw threaded portions 18 of the standards. The collars 19 on the trunnions 15 prevent endwise movement of the rolls and the recesses 20 for the 105 printing surface whether such printing 110

trunnions have their floors opposed to each other, whereby, to admit of expediting the operation of detaching the inking devices, which operation may be effected by simply 5 operating certain of the nuts 17 so as to admit of the boxes approaching each other sufficiently near to permit one of the trunnions of one of the rolls to be lifted from the recess in which it is journaled.

10 In Fig. 1 the ink is supplied to the inking devices by the ink plate whose surface contacts with the inking device on each reciprocation of the bed. If there is but one ink plate the relative positions of the belts with 15 respect to the same will be such that both will receive a supply of ink on each reciprocation of the bed, or when there is a plate at each end of the bed either or both plates may contact with each belt as the bed reciprocates.

22 indicates a series of distributing rolls positioned between the belts 12—12 and arranged so as to contact therewith. The trunnions 23 of these rolls are arranged in 25 cross bars 24 yieldingly held by springs 25 in the standards. As shown in Fig. 1 a series comprising three of these rolls is employed wherein the intermediate roll extends horizontally and the outer rolls extend 30 obliquely to the intermediate roll so that when the belts 12—12 travel in one direction during one movement of the bed and then travel in the opposite direction during the return movement of the bed, these different 35 directions of movement of the belts will cause the outer rolls to change their positions with respect to the intermediate roll at each different movement of the belts. This will have the effect of causing an even

distribution of the ink over the surfaces of 40 the belts 12—12.

Although we have shown and described one embodiment of our invention it is to be understood that we are not to be limited to the specific arrangement and construction of 45 parts since various changes may be made, within the scope of the appended claims without departing from the spirit or sacrificing any of the advantages of the invention.

50 What we claim as new is:

1. In a printing press, the combination with the press frame; of standards arranged on opposite sides of said frame, bearing boxes extending laterally from said standards and adjustable relative to each other, an inking device including a plurality of rolls mounted in said boxes, cross bars yieldably held in said standards, and distributing rolls supported by said cross bars and 60 mounted between said inking rolls.

2. In a printing press, the combination with the press frame; of standards arranged on opposite sides of said frame, an inking device including a plurality of rolls adjustably mounted in said standards, cross bars yieldably held in said standards, and a plurality of superimposed distributing rolls supported by said cross bars, certain of said distributing rolls being arranged obliquely 65 to the others.

65 In testimony whereof we affix our signatures in presence of two witnesses.

ARTHUR B. DAVIS.
ANCEL B. LEFFEL.
